[57] CLAIM

The ornamental design for a delimbing apparatus, as shown and described.

DESCRIPTION

FIG. 1 is a perspective view of a delimbing apparatus showing my new design, the attached vehicle is shown in broken lines for illustrative purposes only;

FIG. 2 is a front elevational view thereof;

FIG. 3 is a top plan view thereof;

FIG. 4 is a bottom plan view thereof;

FIG. 5 is a rear elevational view thereof; and,

FIG. 6 is a side elevational view thereof, the opposite side being substantially identical.

FIGS. 1-5 are broken away to show indeterminate length.
